UNITED STATES PATENT OFFICE.

EUGENE GREGORY, OF MICHIGAN CITY, INDIANA.

BUILDING BLOCK OR SECTION.

1,193,542.

Specification of Letters Patent.

Patented Aug. 8, 1916.

Application filed June 12, 1912. Serial No. 703,217.

To all whom it may concern:

Be it known that I, EUGENE GREGORY, of Michigan City, in the county of Laporte and State of Indiana, have invented certain new and useful Improvements in Building Blocks or Sections; and I hereby declare that the following is a full, clear, and exact description thereof, reference being had to the accompanying drawings, which form 10 part of this specification.

This invention is a novel composite building unit or section for construction purposes; especially designed for use in erecting the walls of buildings for dwellings, 15 factories and the like, and for general structural purposes.

The object of the invention is to produce light, hollow and strong building sections which will be thoroughly braced and may 20 be of any desired size; and which sections can be used like concrete blocks or may be made thin and used as a sheathing.

The particular manner in which the sections are employed in the erection of a wall 25 or building is not material to the present invention which relates particularly to the construction of such sections.

A section constructed in accordance with the invention comprises in brief a foundation 30 frame work, preferably made of narrow strips of wood, metal, or other suitable material, and arranged to form a rectangular frame; and inside of such frame are arranged intersecting vertical and horizontal strips which may be of the same material 35 as the sides of the frame work; and in each square formed by such intersecting strips are intersecting diagonal braces. This framing thus braced may be then wrapped with 40 wire so as to bond it securely and form a basis or support for the paper wrapping, and over this are placed layers of paper or other suitable non-conducting material; the 45 whole is then preferably wrapped with iron wire in two directions; and then covered exteriorly with a preferably water-proof composition of cement, or other suitable material, or compositions of material. Such a section may be of any desired size and contour, but is preferably from two to six 50 inches thick and about four feet square.

In the accompanying drawings I have 55 illustrated a section embodying the invention. As shown therein it comprises first a foundation frame consisting of horizontal

strips 1, and vertical strips 1^a, matched to form a rectangular frame, and these strips may be connected at the corners of the frame by any suitable means, not shown. This foundation frame is braced by vertical and 60 transverse intersecting strips 2, 2^a, which as shown in Figure 1, divide the interior of the frame work into smaller squares. Within these squares are placed X-braces formed of intersecting strips 3, 3^a. All these braces 65 may be composed of wooden or metal strips which are preferably notched at their intersections as indicated in Fig. 2, so that where they intersect they can be fitted to each other in the ordinary way. This foundation work is then preferably wrapped 70 with iron wire as indicated at 4 (Fig. 3). If desired these wires 4 may be wrapped both longitudinally and horizontally around the frame, but wrapping the latter one way 75 ordinarily suffices; and the wraps of the wire may be spaced apart according to the size and desired strength of the section. This wire wrapped frame is then covered with layers of paper or felt, preferably of 80 fiber paper, as indicated at 5; and then the covered frame is again wrapped with iron wire, preferably both vertically and horizontally, as indicated at 6 and 7 in the drawings. Then the wrapped unit is covered 85 with an outer coating of cement, or other suitable material or composition or material, indicated at 8 in the drawings.

In the manufacture of the sections the work of wrapping the foundation frame 90 with wire and covering it with paper or composition material may be largely or wholly performed by machinery, which however forms no part of the present invention; in this way the expense of constructing such sections is reduced to the 95 minimum.

The sections may be made of any desired size and can be fastened to suitable uprights or ordinary studding by nails, or in 100 other desired manner, and form an efficient, warm, moisture-proof, neat appearing, wall. Sections or blocks of any desired size and form may be constructed in this manner according to the nature and design of the wall 105 or building in which they are to be used.

What I claim is:

1. A building section comprising a frame, intersecting bracing strips within the frame, a layer of non heat-conducting material 110

upon such frame, a wrapping of wire around said layer, and an outer composition covering.

2. A building section comprising a frame composed of strips of suitable material, with intersecting strips within the frame and X-braces between the intersecting strips, a non-heat-conducting layer upon the exterior of such frame, a wrapping of wire around said frame, and an outer composition covering.

3. A building section comprising a foundation frame composed of narrow strips of suitable material arranged on edge; intersecting braces arranged within the frame and X-braces between the first braces; a layer of paper or felt upon such frame, a wrapping of wire around said layer, and an outer covering of cement.

4. A building section comprising a foundation frame composed of narrow strips of suitable material arranged on edge, intersecting braces in said frame, a layer of paper

or felt upon such frame, a wrapping of wire, a second wrapping of wire around said frame intersecting the first wrapping of wire around said layer, and an outer covering of cement.

5. A building section comprising a foundation frame composed of narrow strips of suitable material arranged on edge, intersecting strips arranged within the frame, and X-braces between the intersecting strips; a layer of paper or felt upon such frame; a wrapping of wire, a second wrapping of wire around said frame intersecting the first wrapping of wire around said layer, and an outer covering of cement.

In testimony that I claim the foregoing as my own, I affix my signature in presence of two witnesses.

EUGENE GREGORY.
